[57] CLAIM

The ornamental design for a nozzle for vehicle air drying apparatus, as shown.

DESCRIPTION

FIG. 1 is a top plan view of a nozzle for vehicle air drying apparatus showing our new design;

FIG. 2 is front elevational view;

FIG. 3 is a right side elevational view;

FIG. 4 is a left side elevational view;

FIG. 5 is a rear elevational view;

FIG. 6 is a bottom plan view; and

FIG. 7 is a front perspective view thereof.

FIG. 1FIG. 2FIG. 3FIG. 4FIG. 5FIG. 6FIG. 7
